LADDER TAPE

Lawrence J. Rasero, Middletown, Conn., assignor
to The Russell Manufacturing Company, Middletown, Conn., a corporation of Connecticut

Application January 23, 1950, Serial No. 140,005

9 Claims. (Cl. 139—384)

1

This invention relates to improvements in what is known as ladder tape or Venetian blind tape or webbing, which is primarily employed for supporting the slats of so-called "Venetian" blinds and the like, and which comprises a pair of spaced-apart front and back main tapes between which extends transverse textile material constituting the rungs or ladders.

One object of this invention is to provide an improved ladder tape which can have the opposite outside faces of the main tapes woven of strands of different colors, and can have the ladder-warp strands which are in the ladders, interwoven with weft strands or picks of the main tapes in such manner as to be concealed from the opposite outside faces of the main tapes, thus permitting the ladder warps to be of any desired color or colors, since they will be concealed entirely from the opposite outside faces of the main tapes.

Another object of this invention is to provide an improved ladder tape which can have the ladder warps of the ladders interwoven with the main tapes without producing any change in the weave-appearance at the opposite outside faces of the main tapes.

Other objects and advantages will appear to those skilled in the art from the following, considered in conjunction with the accompanying drawings.

In the description and claims, the various parts and steps are identified by specific terms for convenience, but they are intended to be as generic in their application as the prior art will permit.

In the accompanying drawings forming part of the present disclosure, in which certain ways of carrying out the invention are shown for illustrative purposes:

Fig. 1 is an edge view of a fragment of a ladder tape made in accordance with the present invention, in partly-opened-out position;

Fig. 2 is a top plan view of Fig. 1 with part broken away;

Fig. 3 is an enlarged view of the area 3 of Fig. 2;

Fig. 4 is a bottom plan view of Fig. 3;

Fig. 5 is an enlarged sectional view on line 5—5 of Fig. 4, and of Fig. 7;

Fig. 6 is a sectional view on line 6—6 of Fig. 5;

Fig. 7 is an enlarged schematic view of the area 7 of Fig. 4;

Fig. 8 is a view similar to Fig. 7, of a modified construction; and

Fig. 9 is a sectional view on line 9—9 of Fig. 8.

Referring to Figs. 1 to 7 of the drawings show-

2

ing the particular form of the invention chosen for illustration therein, the ladder tape 10 includes two main or body-tapes 11 and 12 connected together by ladders or rungs 13. One of the main tapes such, for example, as 11 may be referred to as the front or face main tape and the other main tape 12 may be referred to as the back or rear main tape. Each ladder 13 interconnects the main tapes 11 and 12 by being connected to the main tapes by being woven thereto at what may be referred to as areas-of-junction 14.

Each of the main tapes 11 and 12 is formed by having warp strands 15 extending throughout the length of the main tapes and interwoven with weft picks of a weft strand 16.

The type of weave employed along those longitudinal portions of each of the main tapes which do not contain any areas-of-junction, may be anything desired. But the areas-of-junction, 20 and preferably the entire longitudinal portions containing the areas-of-junction, are woven by having each main-tape warp strand 15 woven so as to float or extend over two and under two weft picks of the weft strands 16. The main-tape 25 warp strands are woven as single or individual strands, as distinguished from groups of two or more, and they extend on the outer face of the main tape over two picks, and then under two picks, and then extend as repeats of over two and 30 under two along the length of the main tape, and with the corresponding woven portions of each of three successive adjacent main-tape warp strands, in one direction widthwise of the area-of-junction, being successively advanced one 35 pick, and then being repeated in said one direction widthwise of the main tape, that is, each repeat of three corresponding woven parts of each three successive adjacent warp strands start their repeat at the same weft pick. And, as I am primarily concerned with the weave of the present 40 construction in the areas-of-junction, since the ladder-warp strands are to be connected to the main tapes at these locations, I will now give a more detailed explanation of the weave in an 45 area-of-junction.

Thus, referring to Figs. 7, 5 and 3, the three main-tape warp strands 15a, 15b and 15c form one group of three warp strands, and then the next group of three warp strands 15d, 15e and 15f form the next group or repeat of three warp strands. And, of course, each of these groups of warp strands, not only in each area-of-junction, but preferably also throughout the length of the tape, forms a repeat in groups of three warp 55 strands, the corresponding parts of each repeat

of three successive adjacent main-tape warp strands, in one direction widthwise of the area-of-junction, as for example, upward as regards the showing of Fig. 7, begins its repeat at the same weft pick 16a of the weft strand 16. Thus, as we are looking at the outer face of the main tape 11 in Fig. 7, the main-tape warp strand 15a floats or extends over the two weft picks 16a and 16b, then passes down under the two weft picks 16c and 16d and then again floats or extends over the top of the weft picks 16e and 16f, and keeps repeating in this manner throughout the length of the tape. And, similarly, the next-adjacent main-tape warp strand 15b begins its floating or extending over picks, advanced one pick, so that its corresponding floating point extends over the two picks 16b and 16c and thereafter, similarly, under the next two picks and over the following two picks, and so on throughout the length of the tape. And likewise as concerns the third warp strand 15c, which completes this group of three warp strands. And, similarly, as concerns the next repeat group of the warp strands 15d, 15e and 15f, and so on for the full width of the area-of-junction.

Each ladder 13 has a plurality of ladder warps, as most clearly shown in Fig. 3, of which the particular ladder warps 13a, 13b, 13c and 13d will be referred to. The ladder-warp strand 13a is looped over the weft pick 16b at the location 13a1 in Fig. 7, centrally beneath the two float-portions of warp strands 15a and 15b where they extend over the weft pick 16b, and then this same ladder-warp strand 13a floats along beneath all of the weft picks until it comes to the weft pick 16f, whereupon it is next looped over this weft pick 16f at the location 13a2 centrally beneath the two main-tape warp strands 15a and 15b at this location, and so on throughout the length of the woven-in parts of the ladder warps in the area-of-junction. Then, the next-adjacent ladder-warp strand 13b is similarly looped over the weft pick 16c centrally beneath the two adjacent warp strands 15b and 15c at the location 13b1, and extends along freely until it is next looped over the weft pick 16g at the location 13b2. And in similar fashion, the ladder warps 13c and 13d are respectively looped over the weft picks 16b, 16f, and 16c, 16g at the respective locations 13c1, 13c2, and 13d1, 13d2. And similarly for all of the rest of the ladder-warp strands, and for the rest of their looped-over locations in the remainder of the area-of-junction (Fig. 3).

Even where the ladder warps are of the same color as the main-tape warps of the main tape with which they are interwoven, it is desirable that the ladder warps shall not show through to the outer surface of the main tape, as it tends to interrupt the perfection of the weave pattern formed by the main-tape warps in the area-of-junction, and this becomes even more important when the ladder warps are of a different color from the main-tape warps of the main tape with which they are interwoven.

In the case where the ladder warps are of one color and the main-tape warps are of another color, even though a weave be used which tends to conceal a large percentage of the looped-in or woven-in locations of the ladder warps, when the tape is viewed from the outer face, owing to the unavoidable minor variations which occur during the weaving operation, ordinarily there are many places throughout the length of a main tape where parts of the differently-colored ladder warps distinctly show through the outer face of

the main tape, with its consequent objection. I have discovered, however, a type of weave construction that provides a new relationship which completely overcomes this showing-through of the ladder warps.

This new relationship involves several factors of importance. Thus, it will be noted from Fig. 7, that on the upper surface of the main tape over the area-of-junction, the portions of the floats of all of the main-tape warps between the locations of weft picks 16b and 16c, are pressed together in side-by-side contact with one another. And between the picks 16a and 16aa, and between the picks 16d and 16e, portions of all of the main-tape warps are also pressed together in side-by-side contact with one another. Thus, the group of three side-by-side warp floats of the main-tape warps 15a, 15b and 15c in the region between picks 16aa and 16e, are held in close side-by-side contact at the locations 13a1 and 13b1, to thus completely cover the ladder tape portions 13a and 13b. And, of course, the same perfect coverage of ladder warps is provided by all the other repeat groups of three warp floats in the area-of-junction. Also, it will be noted that out of every group of three main-tape warps that pass the pick 16b, two out of the three pass over the top of the pick, and only one passes beneath the pick. And it will be noted from Fig. 7 that as concerns each of the other picks 16c, 16f and 16g, the same two out of three main tape warp relationship also exists, with the same result of perfect coverage of the ladder warps connected to the main tape.

In the modified construction illustrated in Figs. 8 and 9, which respectively correspond to Figs. 7 and 5 illustrating the first form of the invention, the main-tape warps 17 are woven with the weft 18 by a weave that is very similar to the weave shown in Fig. 7, except that instead of employing the weave of Fig. 7 in which each warp goes over two and under two, the weave of Figs. 8 and 9 has each main-tape warp going over two and under one, but repeating transversely of the tape at each three main-tape warps just the same as in the case of the repeats shown in Fig. 7. Thus, beginning with the weft pick 18a, each of the three successive adjacent warp strands 17a, 17b and 17c have this form of over-two-under-one weave with each of three successive adjacent warp strands being advanced one pick, and then the next three warp strands 17d, 17e and 17f form the next repeat group, beginning, of course, at the same weft pick 18a. And similarly to the construction shown in Fig. 7, the ladder warp 19a is looped over the weft pick 18b centrally beneath the two adjacent warp floats of the main-tape warps 17a and 17b at 19a1. And then the ladder warp 19a extends along underneath the weft picks 18c and 18d, and then is next looped over the pick 18e at 19a2, centrally beneath the two adjacent warp floats thereover of the main-tape warps 17a and 17b. And, in similar manner, other ladder warps are respectively looped over weft picks at the locations indicated at 19b1, 19b2; 19c1, 19c2; and 19d1, 19d2, etc. The mode of action giving perfect coverage of the ladder warps with this over-two-under-one weave, is very similar to that of the preceding described over-two-under-two weave.

The important characteristic of the weave that results in this perfect coverage, is that the main-tape warp strands are woven as singles, over two picks, and, under two picks or under one pick, each of three adjacent warps being successively

advanced one pick, and repeated in such groups of three warps.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A ladder tape including: two main tapes, and ladders interconnecting said main tapes at areas-of-junction with said main tapes; each said main tape in each said area-of-junction having main-tape warp strands interwoven with weft picks by a weave in which the warp strands extend as singles on the outer face of the main tape over two weft picks, and then under at least one but not more than two weft picks, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of each main tape and between two successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over one of said two successive weft-picks beneath the space occupied by two adjacent main-tape warp strands which extend over one of said two successive weft-picks, at a number of pick locations longitudinally of the area-of-junction.

2. A ladder tape including: two main tapes, and ladders interconnecting said main tapes at areas-of-junction with said main tapes; each said main tape in each said area-of-junction having main-tape warp strands interwoven with weft picks by a weave in which the warp strands extend as singles on the outer face of the main tape over two weft picks, and then under at least one but not more than two weft picks, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of each main tape and between two successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over each of said two successive weft-picks beneath the space occupied by two adjacent main-tape warp strands which extend over one of said two successive weft-picks, at a number of pick locations longitudinally of the area-of-junction.

3. A ladder tape including: two main tapes, and ladders interconnecting said main tapes at areas-of-junction with said main tapes; each said main

tape in each said area-of-junction having main-tape warp strands interwoven with weft picks by a weave in which the warp strands extend as singles on the outer face of the main tape over two weft picks, and then under two weft picks, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of each main tape and between two successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over one of said two successive weft-picks beneath the space occupied by two adjacent main-tape warp strands which extend over one of said two successive weft-picks, at a number of pick locations longitudinally of the area-of-junction.

4. A ladder tape including: two main tapes, and ladders interconnecting said main tapes at areas-of-junction with said main tapes; each said main tape in each said area-of-junction having main-tape warp strands interwoven with weft picks by a weave in which the warp strands extend as singles on the outer face of the main tape over two weft picks, and then under two weft picks, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of each main tape and between two successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over each of said two successive weft-picks beneath the space occupied by two adjacent main-tape warp strands which extend over one of said two successive weft-picks, at a number of pick locations longitudinally of the area-of-junction.

5. A ladder tape including: two main tapes, and ladders interconnecting said main tapes at areas-of-junction with said main tapes; each said main tape in each said area-of-junction having main-tape warp strands interwoven with weft picks by a weave in which the warp strands extend as singles on the outer face of the main tape over two weft picks, and then under one weft pick, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of each main tape and between two

successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over one of said two successive weft-picks beneath the space occupied by two adjacent main-tape warp strands which extend over one of said two successive weft-picks, at a number of pick locations longitudinally of the area-of-junction.

6. A ladder tape including: two main tapes, and ladders interconnecting said main tapes at areas-of-junction with said main tapes; each said main tape in each said area-of-junction having main-tape warp strands interwoven with weft picks by a weave in which the warp strands extend as singles on the outer face of the main tape over two weft picks, and then under one weft pick, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of each main tape and between two successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over each of said two successive weft-picks beneath the space occupied by two adjacent main-tape warp strands which extend over one of said two successive weft-picks, at a number of pick locations longitudinally of the area-of-junction.

7. A ladder tape including: two main tapes, and ladders interconnecting said main tapes at areas-of-junction with said main tapes; one said main tape in each of its areas-of-junction having main-tape warp strands interwoven with weft picks by a weave in which the warp strands extend as singles on the outer face of the main tape over two weft picks, and then under at least one but not more than two weft picks, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of the main tape and between two successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over one of said two successive weft-picks beneath the space occupied by two adjacent main-tape warp strands which extend over one of said two successive weft-picks, at a number of pick locations longitudinally of the area-of-junction.

8. A ladder tape including: two main tapes, and ladders interconnecting said main tapes at areas-of-junction with said main tapes; one said main tape in each of its areas-of-junction having main-tape warp strands interwoven with weft picks by a weave in which the warp strands extend as singles on the outer face of the main tape over two weft picks, and then under at least one but not more than two weft picks, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of the main tape and between two successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over each of said two successive weft-picks beneath the space occupied by two adjacent main-tape warp strands which extend over one of said two successive weft-picks, at a number of pick locations longitudinally of the area-of-junction.

9. A ladder tape including: two main tapes, and ladders interconnecting said main tapes at areas-of-junction with said main tapes; one said main tape in each of its areas-of-junction having main-tape warp strands interwoven with weft picks by a weave in which the warp strands extend as singles on the outer face of the main tape over two weft picks, and then under two weft picks, and then extend in like repeats along the length of the area-of-junction, and with the corresponding woven parts of each of three successive adjacent main-tape warp strands in one direction widthwise of the area-of-junction, being successively advanced one pick, and then being repeated in said one direction widthwise of the area-of-junction to cause portions of the floats of all of the main-tape warp strands at the outer face of the main tape and between two successive weft-picks, to be pressed together in side-by-side contact with one another throughout the width of the area-of-junction and at a plurality of locations longitudinally of the area-of-junction; and each ladder having ladder warp strands, each of a plurality of said ladder warp strands being looped over each of said two successive weft-picks beneath the space occupied by two adjacent main-tape warp strands which extend over one of said two successive weft-picks, at a number of pick locations longitudinally of the area-of-junction.
